UNITED STATES PATENT OFFICE

FRITZ WOLF, OF BERLIN, GERMANY, ASSIGNOR TO SIEMENS & HALSKE AKTIENGESELLSCHAFT, OF SIEMENSSTADT, NEAR BERLIN, GERMANY

TELEPHONE SYSTEM

Application filed November 17, 1930, Serial No. 496,059, and in Germany December 12, 1929.

The invention relates to a telephone system in which toll lines are multipled in a number of operators' positions but are provided with answering jacks at only one position, the answering jacks being distributed among the different positions according to the usual practice.

The object of the invention is to reduce the number of devices used by an operator at her position to indicate whether a toll line is engaged or disengaged. This is effected in a particularly simple manner by providing the connecting arrangements (cord circuits) at each operator's position with switching devices which can only effect the through connection of a line after a manual operation has been performed at the operator's position to which the required toll line is allotted as a calling line.

An example of the operation of the invention is shown in the accompanying illustration in which two operators' positions PL1 and PL2 are shown together with the necessary answering jacks AK1, AK2 and calling or multiple jacks VK1, VK2, belonging, respectively, to the long distance lines F1 and F2. The cord circuit is shown for the operator's position PL1 only.

The arrangement operates in the following manner:

When a call is received at the operator's position PL1 over the line F1 relay A1 responds over its I winding, closes the contact 1a1 and thereby causes the lamp AL1 to be lighted over the circuit: earth, battery, lamp AL1, contacts 1a1, earth. Relay A1 remains attracted over its II winding in the circuit: earth, contacts 1a1, 2t1, winding II of relay A1, battery, earth. The operator puts the plug St1 into the jack AK1 whereby relay C1 is operated over the circuit: earth, windings II and I of relay C1, plug St1, jack AK1, c-lead of the line F1, to battery and earth in the allotted connecting device not shown in the diagram. Relay C1 then short circuits its high resistance winding II through its contact 3c1 and thereby prevents the engaged line from being seized in known manner. Simultaneously with the operation 50 of relay C1 the relay T1 is energized over

the circuit: earth, battery, relay T1, c-lead, line F1, jack AK1, plug St1, relay C1, earth. Relay T1 responds and opens its contacts 17t1 and 18t1 so that the relay A1 cannot be energized again during the connection by a call over another line in whatever way it 55 may be connected to the line F1. Relay C1 also closes its contacts 4c1 and 5c1.

The operator now operates the key T and opens contacts 6 and 7 and closes contacts 8 and 9 respectively, and thereby connects her set Abf to the calling line F1. She inquires as to the number and location of the wanted party and then communicates over an order wire (not shown on the drawing) with the operator at the position PL2, to which toll lines such as F2 extending to the desired point are allocated as calling lines. The second operator now notes the busy or idle condition of the lines in the desired group and tells the first operator which one to use. Assuming that toll line F2 is the one selected, the second operator operates the key Tb2 whereby a circuit for relay C2 in the first operator's cord circuit is prepared by connecting the sleeve of jack VK2 to the winding of relay T2. 70

The operator at position PL1 now inserts the plug St2 in the jack VK2 and closes the circuit prepared for relay C2 with the result that this responds over the circuit: earth, 80 windings II and I of relay C2, plug St2, jack VK2, c-lead of the line F2, contact 10 of the switch operated by the key Tb2, relay T2, battery, earth. Relay C2 closes its contact 11c2 and guards the engaged line from being seized by the short circuiting of its winding II. In addition it closes its contacts 12c2 and 13c2 to which the calling line F1 is connected to the required line F2 by the return of the answering key to close contacts 85 6 and 7.

The insertion of the plug St2 in the jack VK2 also operates relay T2 in series with relay C2 causing its contacts 14t2 and 15t2 to open so that relay A2 cannot be energized by 90 an incoming call transmitted by one line or another connected to the line F2.

When the conversation is finished and the operator at the position PL1 has received a disconnect signal in known manner, she pulls 100

out the plugs S_{t1} and S_{t2} . The circuit for relays C_1 and T_1 is thus broken, these relays thereby releasing. When this takes place the contacts $3c_1$, $4c_1$ and $5c_1$ are opened and 5 $2t_1$, $17t_1$, $18t_1$ and $21t_1$ are closed. The circuit for relays C_2 and T_2 is also broken with the result that the contacts $11c_2$, $12c_2$ and $13c_2$ are opened and $14t_2$, $15t_2$, $16t_2$ and $19t_2$ are closed. The key T_{b2} still being de- 10 pressed, the operator at the position PL_2 is notified by the lighting of the lamp SL_2 over the circuit: earth, battery, contact $16t_2$, lamp SL_2 , contact 20, closed by the switch effected by key T_{b2} , earth, that the conversation is 15 finished. She puts the key T_{b2} into its normal position so that everything is restored to its original condition.

What is claimed is:

1. In a telephone system, two switchboards, 20 a group of trunks terminating in answering jacks in the first switchboard and in multiple jacks in the second switchboard, a second group of trunks terminating in answering jacks in the second switchboard and in multiple jacks in the first switchboard, a cord circuit at the first switchboard for connecting trunks of the first and second groups by way of their respective answering and multiple jacks, and means controlled from the second switchboard for completing the connection by closing normally open points in the cord circuit.
2. In a telephone system, two switchboards, 35 a group of trunks terminating in answering jacks in the first switchboard and in multiple jacks in the second switchboard, a second group of trunks terminating in multiple jacks in the first switchboard and in answering jacks in the second switchboard, a cord circuit at the first switchboard for establishing connections between a trunk line in the first group and a trunk line in the second group, a plurality of normally open points in the talking strands of said cord circuit, means 40 for automatically closing certain of the normally open points in the cord circuit when the operator at the first switchboard plugs it into an answering jack, and means controlled by the operator at the second switch- 45 board for closing the remaining normally open points in the cord circuit when the operator at the first switchboard plugs it into a multiple jack.
3. In a telephone system, two switchboards, 55 a group of trunks terminating in answering jacks in the first switchboard and in multiple jacks in the second switchboard, a second group of trunks terminating in multiple jacks in the first switchboard and in answering jacks in the second switchboard, a cord circuit at the first switchboard for establishing connections between a trunk line in the first group and a trunk line in the second group, a plurality of normally open points in the talking strands of said cord circuit, means

for automatically closing certain of the normally open points in the cord circuit when the operator at the first switchboard plugs it into an answering jack, means controlled by the operator at the second switchboard for closing the remaining normally open points in the cord circuit when the operator at the first switchboard plugs it into a multiple jack, and means for automatically signalling said second operator when said first operator removes the cord from the multiple jack. 70

4. In a telephone system, a cord circuit having a plurality of normally open points in the talking strands, answering and multiple jacks, a relay for closing certain of the normally open points when one end of the cord circuit is plugged into an answering jack, another relay for closing the remaining normally open points when the other end of the cord circuit is plugged into an assigned multiple jack, and means for controlling the operation of said second relay at the position assigning the multiple jack. 80

5. In a telephone system, an operator's position, incoming and outgoing trunk lines, a 90 cord circuit at said position for connecting the trunk lines, said cord circuit having normally open points in the talking strands, a relay for closing said normally open points, another operator's position for assigning outgoing trunks, and means at said assigning operator's position for controlling the operation of said relay. 95

6. In a telephone system, a trunk line terminating in an answering jack and a plurality 100 of multiple jacks, a relay permanently connected to the sleeve of said answering jack, means for operating said relay when a call over said trunk line is answered, means for connecting said relay to the sleeve of each of said multiple jacks when a call is to be extended over said trunk line, a signal operative responsive to the last mentioned means, and means responsive to the extension of said call over said trunk line for operating said relay to disconnect said signal. 105

7. In a telephone system, a trunk line terminating in an answering jack at one position and in a multiple jack at another position, a relay at said answering position permanently connected to the sleeve of said answering jack, means for operating said relay when a call over said trunk line is answered, means at said answering position for connecting said relay to the sleeve of said multiple jack when a call is to be extended over said trunk line, a signal at said answering position operative responsive to the last mentioned means, and means responsive to the extension of said call over said trunk line 115 for operating said relay to disconnect said signal. 120

8. In a telephone system, a trunk line terminating in an answering jack and a plurality of multiple jacks, said answering jack 125

being located at a first operator's position and each one of said multiple jacks being located at a different operator's position, a cord circuit at said first operator's position

- 5 having normally open points in the talking strands, a current source permanently connected to the sleeve of said answering jack, means responsive to said source for closing the normally open points in said cord circuit
10 when said first operator answers a call over said trunk line, and manually controlled means at said first operator's position for connecting said source to the sleeve of said multiple jacks when any other operator
15 desires to extend a call over said trunk line.

9. In a telephone system, an operator's position, a cord circuit thereat having normally open points in the talking strands, an answering jack, means responsive to the plugging in of one end of said cord into said answering jack for closing certain of said normally open points in said talking strands, multiple jacks, and means responsive to the plugging in of the other end of said cord into an assigned multiple jack for closing the remaining open points in said talking strands.

10. In a telephone system, an operator's position, a cord circuit thereat having normally open points in the talking strands, an answering jack, means responsive to the plugging in of one end of said cord into said answering jack for closing certain of said normally open points in said talking strands,

35 multiple jacks, means responsive to the plugging in of the other end of said cord into an assigned multiple jack for closing the remaining open points in said talking strands, and means at a second operator's position
40 for preventing the remaining open points in the talking strands of said cord circuit from closing when the operator at said first-mentioned operator's position plugs said cord into a busy or unassigned multiple jack.

45 11. In an operator's position, a cord circuit having a plurality of normally open points in the talking strands, means responsive to the plugging of said cord into an answering jack for closing certain of the said open points, a second operator's position, multiple jacks at said first position assigned by the operator at said second position, and means controlled by the operator at said second position for closing of the remaining open points in the talking strands of the cord circuit when the same is plugged into an assigned multiple jack.

In witness whereof, I hereunto subscribe my name this 24th day of October, A. D. 60 1930.

FRITZ WOLF.
